[57] CLAIM

The ornamental design for a handle for a knife or similar article, as shown and described.

DESCRIPTION

FIG. 1 is a perspective view taken from the top and left end of a handle for a knife or similar article showing my new design;

FIG. 2 is a top plan view thereof;

FIG. 3 is a front elevational view thereof, the rear elevational view being a mirror image thereof;

FIG. 4 is a bottom plan view thereof;

FIG. 5 is an end elevational view on an enlarged scale taken in the direction of lines 5—5 of FIG. 3; and

FIG. 6 is an end elevational view on an enlarged scale taken in the direction of lines 6—6 of FIG. 3.
